(57) **CLAIM**

The ornamental design for a makeup case with LED lighted mirror, as shown and described.

DESCRIPTION

FIG. 1 is a perspective view of a makeup case with LED lighted mirror showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the makeup case with LED lighted mirror, shown in an environment of use.

The broken lines shown in the drawings represent portions of the makeup case with LED lighted mirror that form no part of the claimed design.
